A. B. CHANCE.
CROSS ARM BACK TRUSS AND CLAMP.
APPLICATION FILED FEB. 17, 1917.

Patented Dec. 9, 1919.

INVENTOR:

ALBERT B. CHANCE.

BY Frederick R. Parker
ATTORNEY.

UNITED STATES PATENT OFFICE.

ALBERT B. CHANCE, OF CENTRALIA, MISSOURI.

CROSS-ARM BACK-TRUSS AND CLAMP.

1,324,585.

Specification of Letters Patent.

Patented Dec. 9, 1919.

Application filed February 17, 1917. Serial No. 149,263.

To all whom it may concern:

Be it known that I, ALBERT B. CHANCE, a citizen of the United States of America, residing at Centralia, in the county of Boone 5 and State of Missouri, have invented a new and useful Cross-Arm Back-Truss and Clamp, of which the following is a specification, reference being had to the accompanying drawings, illustrating the preferred 10 forms of the invention.

My invention relates to trusses and also to clamps.

The principal objects of my invention are, to provide an improved truss-like brace for 15 cross-arms on poles, or for other devices, as herein more fully set forth; to provide an improved cable messenger hanger as herein more fully set forth; to provide an improved clamp as herein more fully set forth; 20 and to provide other improvements in the devices of the invention as herein set forth.

Other objects will be apparent from the following specification.

In the accompanying sheet of drawings 25 illustrating the preferred forms of my invention, Figure 1 is a perspective view of a portion of a pole, a cross-arm, and the improved cross-arm back-truss and clamp of my invention; Fig. 2 is a side elevation of a 30 portion of a pole, a cross-arm, and the clamp of my invention, looking at the end of the cross-arm; Fig. 3 is a view similar to Fig. 2, with the cross-arm of Fig. 2 removed; Fig. 4 is a side elevation of the clamp shown in 35 Figs. 1, 2 and 3, with the clamping bolt removed; Fig. 5 is a plan view of the clamp shown in Fig. 4, without the clamping bolt; Fig. 6 is an edge elevation of the two clamping members of the clamp shown in Fig. 4, 40 shown in separated relation; Fig. 7 is a plan view of the shoe which is attached to the ends of the cross-arm in Fig. 1; and Fig. 8 is an elevation of the shoe shown in Fig. 7.

Like characters refer to like parts in the 45 several figures.

In the preferred forms of my invention, illustrated in the drawings, 1 is a pole, such as a telephone or telegraph pole, 2 is a cross-arm carried by the pole 1, 3 3 are the usual 50 cross-arm braces for the cross-arm 2, and 4 4 are the usual insulator pins which are carried by the cross-arm 2.

B B are shoes which are attached to the respective ends of the cross-arm 2 by a bolt 55 5 for each, which extends through the shoe

B and through the cross-arm 2, preferably as shown in Fig. 1. A is a clamp which is attached to the back side of the pole 1 in the position shown in Fig. 1. 6 is a heavy rod which extends through the clamp A as 60 shown in Fig. 1, the ends of the rod 6 being attached to the shoes B B preferably as shown in Fig. 7 so that the cross-arm 2, the rod 6, and the pole 1 between the middle of the cross-arm 2 and the middle of the rod 6, 65 form a truss the primary object of which is to brace the cross-arm 2 against tensional stresses in either direction in the line wires or conductors which are carried by the pins 4 4, or against other stresses tending to 70 strain the cross-arm 2 out of place. The truss member 6 may be tightened up as much as desired, by means of one or more nuts 7 on each end thereof as shown in Fig. 7. The truss member 6 is preferably tightly 75 clamped in the clamp A so as not to slip therethrough when the truss is under a strain. A truss of this character will prevent the cross-arm from being twisted out of place or torn from the pole under unusual 80 stresses such as are occasioned by the breaking of one or more of the line wires under extreme weather conditions.

The clamp A may be attached to the pole 1 as shown in Figs. 1 and 2, or as shown in 85 Fig. 3. In Fig. 6 it will be seen that the clamp A is composed of two clamping members 11 and 12. I preferably thread the hole 13 in the clamping member 12, and make the hole 14 in the clamping member 11 large 90 enough to clear the clamping bolt 8. The bolt 8 is preferably threaded on both ends to receive clamping nuts as shown in Figs. 2 and 3. The clamping member 12 is threaded onto the bolt 8 and the latter is extended 95 through the pole 1 as shown in Figs. 2 and 3. Then, in Figs. 1 and 2, the cross-arm 2 is put in place on the bolt 8, and the nut, or nut and washer, 9 is tightened up on the bolt 8, the member 12 of the clamp A, and the nut, 100 or nut and washer, 9 serving as clamping members to clamp the pole 1 and cross-arm 2 tightly together therebetween. Now the truss member 6 may be put in place between the clamping members 11 and 12 105 of the clamp A, and the nut 10 tightened up on the bolt 8 against the clamping member 11 as shown in Figs. 1, 2 and 3, the member 12 of the clamp A, and the member 11 and nut 10 serving as clamping 110

members to clamp the truss member 6 tightly in place between the members 11 and 12 of the clamp A as shown in Figs. 1 and 2. Thus it will be seen that in the device of this invention there are two independent clamps provided, one by member 12, nut and washer 9, and a portion of the bolt 8, for clamping the pole and cross-arm together, and the other by the member 12, the member 11 and nut 10, and a portion of the bolt 8, for clamping the truss member 6 in place.

I may also use my clamp A for a cable messenger clamp if I desire, or for other purposes. As a cable messenger clamp I may use it in connection with a cross-arm 2 as shown in Fig. 2, or without a cross-arm as shown in Fig. 3. In either Fig. 2 or Fig. 3, the cable messenger strand is clamped between the members 11 and 12 of the clamp A the same as the truss member 6 is clamped in place in the clamp A. In Fig. 2 the member 12, and the nut, or nut and washer, 9 clamp the pole 1 and cross-arm 2 together therebetween, and the member 12, and the member 11 and nut 10 clamp the cable messenger strand between the members 11 and 12. In Fig. 3, the member 12, and the nut, or nut and washer, 9 clamp the pole 1 therebetween, and the member 12, and the member 11 and nut 10 clamp the cable messenger strand 6^a between the members 11 and 12, in this case also the two independent clamps being provided.

I may also use various modifications of the constructions set forth, if I desire.

The clamping member 12 is preferably provided with pointed projections 17 thereon adapted to embed themselves into the pole 1 or other suitable portion to help position the member 12 in place. The clamping member 11 is preferably provided with a projecting lug 15 thereon, extending into a recess 16 in the member 12, for holding the member 11 from turning on the bolt 8 while the nut 10 is being tightened up.

The construction of the shoe B can be well understood from Figs. 7 and 8, and need not, therefore, be further described.

I do not wish to limit this invention to the particular details herein set forth, as various modifications thereof may be made or utilized without departing from the scope of the appended claims.

I also wish it to be understood that the several features of the invention may be used either singly or collectively without de-

parting from the scope of the appended claims.

What I claim as my invention is:

1. The combination with a pole and a cross-arm therefor, of a bolt extending through the pole and cross-arm and threaded on both ends, a clamp carried by the said bolt on the opposite side of the pole from the cross-arm, the said clamp having a pair of clamping members one of which is screwed onto the said bolt, a nut carried by the bolt on the opposite end thereof from the said clamp for clamping the cross-arm to the pole, a shoe for each end of the cross-arm and attached thereto, a supporting member for the cross-arm extending through the said clamp and having the ends thereof attached to the said shoes, and a nut carried by the said bolt for causing the said clamp to tightly clamp the said supporting member therein.

2. The combination with a pole and a cross-arm therefor, of a bolt extending through the pole and cross-arm, a clamp carried by the said bolt on the opposite side of the pole from the cross-arm, the said clamp having a pair of clamping members one of which is secured to the said bolt, means carried by the said bolt for clamping the cross-arm to the pole, a shoe for each end of the cross-arm and attached thereto, a supporting member for the cross-arm extending through the said clamp and having the ends thereof attached to the said shoes, and means for causing the said clamp to tightly clamp the said supporting member therein.

3. The combination with a pole and a cross-arm therefor, of a bolt extending through the pole and cross-arm, a clamp carried by the said bolt on the opposite side of the pole from the cross-arm and having a portion thereof secured to said bolt, a supporting member for the cross-arm extending through the said clamp and having the ends thereof attached to the end portions of the cross-arm, and means on the said bolt for clamping the cross-arm to the pole and the said supporting member in the said clamp independently.

As inventor of the foregoing I hereunto subscribe my name, this 12 day of February, 1917.

ALBERT B. CHANCE.
